UNITED STATES PATENT OFFICE.

JOHN B. BAXTER, OF TROY, NEW YORK, ASSIGNOR TO COVERT MANUFACTURING COMPANY, OF WATERVLIET, NEW YORK, A CORPORATION OF NEW YORK.

SNAP HOOK.

Application filed November 2, 1926. Serial No. 145,887.

This invention relates to improvements in snap hooks of the kind known as "bolt-snaps" that have a spring pressed bolt sliding in a tubular body or barrel, the outer end 5 of the bolt normally engaging the bill of the hook, and the bolt being provided with a thumb piece for operating the same, the shank of the thumb piece working in a longitudinal guide slot in the forward part of 10 the tubular body or barrel.

In snap hooks of the class referred to there is the "turned-over" type, in which the blank is cast substantially trough-shape or of U-shape form in cross section and the 15 upper portions of the sides are afterward turned over to form the barrel, the forward portions of the sides being of less depth than the rear portions to provide the longitudinal guide slot extending from the hook or forward end of the barrel. There is also what 20 is known as the "core" type wherein the barrel or tubular body blank is cast with a core. Heretofore in the "turned-over" type the forward portions of the sides of the trough 25 shaped blank have been formed of equal depth throughout, the upper edge faces of said side wall portions extending in lines parallel with the axis of the tubular blank, and in forming the barrel, when the rear 30 deeper portions of the sides were brought together, it drew the back parts of the forward sections of said sides closer together than the front parts thereof, the guide slot being wider at the front than at the rear 35 with a tendency toward wedge shape. This left the bolt free and loose at the front end of the guide slot with a tendency to shoot upward out of alignment with the bill of the hook, a serious fault, dangerously 40 impairing the efficiency of the device, while the narrow back part of the guide slot caused the bolt to bind at the back of the slot. Furthermore, the tumbling and finishing of the snap tends to crowd and close in the front 45 of the barrel resulting in still further narrowing the slot at the back and preventing free operation of the bolt, necessitating punching, which only increases the difficulty since in order to press the slot open far 50 enough at the back part thereof, the front end, which naturally opens with less pressure, was opened to too great an extent.

Similar trouble has been encountered in the manufacture of the "core" type of bolt 55 snap. These have been cast with the side

walls of the guide slot parallel with each other and with the axis of the blank. In the tumbling and finishing treatment, the front of the barrel became tumbled in and had to be punched open to permit the insertion of the bolt, which left the guide slot wedge shaped, wider and flaring at the front part, leaving the bolt loose at the front end of the slot and causing the same to bind at the back end thereof.

The object of the present invention is to improve the manufacture of the class of snap hooks referred to, to provide an improved construction of body casting or blank whereby the difficulties referred to are overcome and an improved bolt snap provided in which the bolt is free to slide within the barrel while properly confined at the front of the barrel to prevent looseness and lateral or upward play.

The invention, with other objects and advantages thereof, and the particular construction and arrangement of parts comprising the same will be understood from the hereinafter detailed description, when considered in connection with the accompanying drawings forming part hereof and illustrating embodiments of the invention.

In the drawings:

Figure 1 is a top plan view of a bolt snap 85 constructed in accordance with the present invention.

Fig. 2 is a side elevation.

Fig. 3 is a side elevation of the casting or blank.

Fig. 4 is a top plan view of the casting or blank.

Fig. 5 is a section on the line X—X of Figure 3.

Fig. 6 is a section on the line Y—Y of 95 Figure 3.

Fig. 7 is a section on the line Z—Z of Figure 2.

Fig. 8 is a top plan view of a casting or blank for a "core" type snap constructed in 100 accordance with the invention.

Fig. 9 is a section on the line A—A of Figure 8.

While in the drawings two specific embodiments of the invention are illustrated, it will 105 be understood that changes and modifications of the particular constructions shown may be made and the invention embodied in other forms as will appeal to those skilled in the art and falling within the scope of the 110

appended claims, without departing from the spirit of the invention.

Referring to a detailed description of the particular embodiment of the invention

- 5 illustrating Figures 1 to 7 of the drawings, A designates the body or barrel portion having a hook B at one end and a loop C at its other end. D designates the bolt provided with a thumb piece d. a is the guide slot in 10 the forward portion of the barrel for the shank d' of the thumb piece d, and E is a coiled spring interposed between the loop end of the body and the inner end of the bolt D.
- 15 The body or barrel portion A is cast trough-shape with sides having rear portions or sections b—b and forward sections c—c, the latter being of less height or depth than the former.
- 20 In accordance with the present invention the forward section c—c of the sides of the blank are of greater depth or height at the front and gradually slope to the rear, so that when the sides are turned over in the 25 usual way to form the barrel a guide slot a will be provided which is narrower at the front end of the barrel than at the rear, said slot gradually increasing in width from front to rear, allowance being made for the 30 drawing of the back portions of the wall sections c—c closer together than the front portions thereof in the turning over of the sides, and also for pressing the forward end portion of the barrel open to insert the bolt, 35 should this be necessary, after the tumbling and finishing operation, without leaving the slot a V-shaped or flaring and too much open at the front.

In Figures 9 and 10 of the drawings is 40 illustrated an embodiment of the invention as applied to the "core" type bolt snap. F designates the body or barrel portion of the snap having at its ends the hook G and loop H. f designates the guide slot in the forward portion of the barrel F, said slot being of the same shape as the shape of the guide slot in the construction illustrated Figures 1 to 7, the opposing side walls f' of the slot f diverging from front to rear, said slot 45 being narrower at the front and gradually increasing in width toward the rear.

It will be noted that the improved construction hereinbefore set forth is of a simple, practical nature, easy to manufacture, 50 and entirely overcomes the difficulties hereinbefore referred to, the V-shaped or open mouthed slot and the attendant dangers and weakness from the bolt sliding outwardly or upwardly at the front being completely

eliminated, the improved structure providing for free backward operation of the bolt while holding the same down at the front against upward play.

What I claim is:

1. A bolt snap hook casting or blank having a barrel provided with a longitudinal slot in its upper side at the forward part thereof, the opposing side walls of said slot diverging from the front end portion of the barrel towards the rear thereof. 65

2. A bolt snap hook casting or blank having a barrel provided with a longitudinal guide slot in its upper side at the forward part thereof, said slot being narrower at the front thereof at the front end portion of the 75 barrel than at the rear.

3. A bolt snap hook casting or blank having a body or barrel part substantially U-shaped in cross section the side walls of which are adapted to be bent in toward each other, forward opposing portions of said side walls being of less depth than rear wall portions thereof, and said forward portion being of greater depth at their front than at their rear to provide a longitudinally extending guide slot narrower at the front of the barrel than at its rear part. 85

4. A bolt snap hook casting or blank having a body or barrel part of substantially U-shaped form in cross section the side walls of which are adapted to be bent in toward each other, forward opposing portions of said side walls being of less depth than rear portions thereof, and said forward opposing portions being of greater depth at the front and gradually sloping rearwardly to provide a longitudinally extending guide slot narrower at the front and gradually increasing in width toward the rear. 90

5. A bolt snap hook having a barrel provided with a hook at one end thereof, said barrel having a slotted portion and opening to the interior thereof, a bolt in the barrel adapted to cooperate with the hook to close the same, and an actuating member for the bolt projecting outwardly through the slotted portion of the barrel, the slotted portion of the barrel being formed to provide a relatively constricted portion for reception of the actuating member when the bolt is in 100 closed position to limit lateral play thereof, the rear portion of the slot permitting relatively free movement of the actuating member when shifting therein. 105

In testimony whereof I hereunto affix my 110 signature.

JOHN B. BAXTER.
